Patented Aug. 18, 1959

185,913

HANDLE FOR KITCHEN UTENSILS AND SIMILAR ARTICLES

Richard S. Latham, Chicago, Ill., assignor to Eko Products Company, Chicago, Ill., a corporation of Illinois

Application September 19, 1958, Serial No. 52,698

Term of patent 14 years

(Cl. D44—29)

Fig. 1 is a side elevational view of a handle for kitchen utensils and similar articles showing my new design.

Fig. 2 is a top plan view thereof.

Fig. 3 is an end view thereof.

Fig. 4 is a section taken on line 4—4 of Fig. 1.

Fig. 5 is a section taken on line 5—5 of Fig. 1.

I claim:

The ornamental design for a handle for kitchen utensils and similar articles, as shown.
